METHOD AND APPARATUS FOR PRODUCING

MULTIPLE SHEET GLAZING UNITS

John A. Woods, Lancaster, Ohio, Donald E. Sharp, deceased, late of Maumee, Ohio, by Ohio Citizens Trust Co., executor, Toledo, Ohio, and Alfred E. Badger, Maumee, Ohio, assignors to Libbey-Owens-Ford Glass Company, Toledo, Ohio, a corporation of Ohio
Continuation of application Ser. No. 567,185, Feb. 23, 1956, which is a continuation of application Ser. No. 300,884, July 25, 1952. This application Apr. 12, 1960, Ser. No. 21,632

3 Claims. (Cl. 65—58)

The present application is a continuation of application Serial No. 567,185, filed February 23, 1956, now abandoned, which is a continuation of application Serial No. 300,884, filed July 25, 1952, now abandoned.

This invention relates broadly to all-glass multiple sheet glazing units. In particular, it relates to an apparatus and method for sealing together the marginal edge portions of spaced sheets of glass to produce a hermetically sealed glazing unit, the sides of which are formed by the union of said marginal edge portions.

Multiple sheet glazing units may be described generally as comprising two or more sheets of glass which are sealed entirely around their marginal edge portions in spaced relation to provide a hermetically sealed dead air space therebetween. Due principally to their insulating and condensation preventing qualities, such units have become well established fixtures in the building trades and have found wide usage as windows for buildings, show cases, vehicles, refrigerators, and the like.

In the early development of the multiple sheet glazing art, it was customary to seal together the marginal edge portions of the spaced sheets of glass by means of strips of a substantially impervious material which were placed between said portions and bonded thereto in any suitable manner. In many cases, the seal so produced was found not to be hermetic and the unit thus impractical for the purposes of improved insulation and the prevention of condensation. As well, in other instances, the sealing process was found to be so cumbersome and expensive that production on a mass basis was practically impossible.

It has been found in accordance with this invention, that a hermetically sealed glazing unit can be formed entirely of glass by means of a method which is relatively simple, inexpensive, and well-suited to mass production techniques.

It is therefore an object of this invention to provide a hermetically sealed, all-glass multiple sheet glazing unit and in particular to provide a relatively simple and inexpensive method of forming such units.

Another object of this invention is to provide a novel method for sealing together the marginal edge portions of spaced sheets of glass to form a hermetically sealed space therebetween.

Another object of this invention is to provide a method of producing multiple sheet glazing units in which the marginal edge portions of spaced sheets of glass are heated to the bending temperature thereof and fused in sealing relation with one another.

Still another object is to provide a novel apparatus for producing all-glass multiple sheet glazing units in accordance with the method of this invention.

Still another object is to provide an apparatus for producing multiple sheet glazing units comprising a furnace, a heat source in the furnace, means for supporting sheets of glass in fixed spaced face-to-face relation, and means for moving said supporting means and heat source

2

relative to and past one another to progressively seal the edge portions of the sheets together.

Briefly stated, this invention contemplates the production of hermetically sealed glazing units made entirely of glass by means of a method and apparatus in which two or more sheets of glass are supported in fixed spaced face-to-face relation and moved past concentrated heat sources to cause the marginal edge portions thereof to unite and thereby seal off a dead air space between said sheets. Thus, according to the invention, concentrated heat sources may be directed to first one and then the other pair of opposite marginal edge portions of the glass sheets, as they are supported in fixed spaced relation and moved therepast, to cause said edge portions to become molten and unite with one another. Or, if preferred, the marginal edges of the glass sheets can be sequentially sealed by subjecting first one edge and then another edge to the action of the heating means.

In the accompanying drawings, wherein like numerals are employed to designate like parts throughout the same:

FIG. 1 is a perspective view of an all-glass multiple sheet glazing unit produced in accordance with this invention;

FIG. 2 is a perspective sectional view of one corner of the glazing unit taken substantially along line 2—2 of FIG. 1;

FIG. 3 is an over-all perspective view of an apparatus for producing the glazing unit and showing the furnace, conveyor, and burners;

FIG. 4 is a fragmentary sectional view of marginal edge portions of one side of spaced sheets of glass prior to being subjected to a concentrated heat source;

FIGS. 5 to 7 are fragmentary sectional views of said edge portions as the heat source is applied thereto and they are caused to soften and bend into contacting relation with one another;

FIG. 8 is a fragmentary sectional view of said edge portions after they have been fused under the influence of said heat source to hermetically seal the side of the glazing unit;

FIG. 9 is a representation of a photograph of a cross section of a typical seal for a side of a glazing unit produced in accordance with this invention and showing by illumination and magnification the flow lines of the fused portions of said side;

FIG. 10 is a fragmentary perspective view of a tray with the spaced glass sheets supported thereon;

FIG. 11 is an enlarged plan view of one of the supporting arms of the tray in supporting position;

FIG. 12 is a sectional view of the supporting arm taken substantially along line 12—12 of FIG. 11;

FIG. 13 is a longitudinal sectional view of the furnace, taken substantially along line 13—13 of FIG. 3, and showing the tray prior to its movement past one of the burners;

FIG. 14 is a transverse sectional view of the furnace, taken substantially along line 14—14 of FIG. 13, with the tray removed;

FIG. 15 is a detailed perspective view of an adjusting device for a "knock-out" pin adapted to engage the tray supporting arms and move the same to a non-supporting position;

FIG. 16 is an enlarged transverse sectional view of a portion of the furnace and one of the burners, similar to FIG. 14 but showing the tray in operative relation with one of the burner heads;

FIG. 17 is an enlarged detailed sectional view of one of the pivotable hinge connections for the burner head of FIG. 16;

FIG. 18 is a plan view of one of the burners and a portion of the furnace shown in FIG. 16;

FIG. 19 is a transverse sectional view of the burner of FIG. 18 taken substantially along the line 19—19;

FIG. 20 is a plan view of a limiting device for the burner of FIG. 18, taken substantially along line 20—20 of FIG. 19;

FIG. 21 is a front view of one of the burner heads;

FIG. 22 is a longitudinal sectional view of the burner head, taken substantially along line 22—22 of FIG. 21, and the gas inlet and coolant inlet and outlet thereto;

FIG. 23 is an enlarged transverse sectional view of the burner head, taken substantially along line 23—23 of FIG. 22;

FIG. 24 is a transverse sectional view of the burner head, taken substantially along line 24—24 of FIG. 22;

FIG. 25 is a transverse sectional view of the burner head, taken substantially along line 25—25 of FIG. 22;

FIG. 26 is a transverse sectional view of the burner head, taken substantially along line 26—26 of FIG. 22; and

FIG. 27 is a sectional view, taken substantially along line 27—27 of FIG. 22 and showing the gas inlet and coolant inlet and outlet of the burner head.

Referring now to the drawings, there is shown in FIG. 3 a perspective view of an apparatus 30 by means of which an all-glass, multiple sheet glazing unit 31 may be produced in a manner to be hereinafter described. This apparatus includes a generally U shaped, horizontally movable conveyor 32, over which are mounted, in order of use, a preheating compartment 33 and a furnace 34, conforming in shape generally to said conveyor. Within the furnace there are arranged, between the entrance 35 and exit 36 thereof, a first sealing area A, a second sealing area B, and an annealing area C. Disposed outwardly of the furnace at opposite sides of sealing areas A and B are burners 37.

The all-glass, multiple sheet glazing unit 31, produced in accordance with this invention, comprises upper and lower sheets of glass 38 and 39, respectively, and side portions 40 between the marginal edge portions of said sheets, forming therebetween an enclosed space 41. Disposed toward an edge or corner of one sheet of the unit is a dehydration hole 42 (FIG. 1) which may be hermetically sealed to seal off the enclosed space 41.

More particularly, the side portions 40 of the unit are composed of an inner wall 43 substantially perpendicular to upper and lower sheets 38 and 39 and an outer wall 44 angularly disposed thereto to form an enlarged base portion 45 adjacent the marginal edge portions of said lower sheet. Thus, enclosed space 41 is substantially rectangular in cross section and the outer periphery of the unit substantially trapezoidal. The corners of enclosed space 41 at the intersection of inner wall 43 and sheets 38 and 39 are rounded or filleted, as best shown in FIG. 9.

As previously mentioned and in a manner to be more fully described hereinafter, the all-glass unit 31 is produced by assembling the upper and lower sheets 38 and 39 in fixed spaced relation, as shown in FIG. 4, properly preheating the sheets, and moving them past concentrated heat sources from burners 37 to cause the marginal edge portions thereof to progressively soften, as shown in FIG. 5, unite, as shown in FIGS. 6 and 7, and ultimately become sealed to one another, as in FIG. 8.

As assembled and prior to being sealed, upper sheet 38 is relatively larger than lower sheet 39 such that a peripheral portion of said upper sheet extends outwardly beyond the marginal edge of the lower sheet. It is also good practice to remove a small portion 46 of each corner of the upper sheet (FIG. 10), to prevent undue accumulation of the marginal edges of said upper sheet at the enlarged base portions 45 of each corner of the sealed unit.

When the spaced sheets are moved therewith, the concentrated heat sources are directed toward the marginal edge portions of opposite sides of the spaced sheets in

such a manner as to initially cause the edge portions of the upper sheet 38 to soften and bend downwardly toward lower sheet 39 and those of the lower sheet to curl upwardly a slight amount (FIG. 5). Toward the completion of the passage of the sheets past the heat sources, the edge portions of the upper sheet will bend further such that the edges thereof will unite with the edge portions of the lower sheet adjacent said lower sheet (FIG. 6). Further heating will cause the united marginal edge portions to become more molten and the line of fusion between the same to increase, as shown in FIG. 7. At the completion of the passage of the sheets past the heat sources, the marginal edge portions of the opposite sides of the sheets will be firmly united and fused to one another at the broad base portion 45 (FIG. 8) to form a seal therebetween.

This seal has been found to be exceptionally strong and permanent rather than a source of weakness in the unit. To illustrate the manner in which the marginal edge portions are finally united, a photograph was taken of a magnified cross section of a typical seal produced in accordance with this invention and which had been illuminated from the rear, and is represented in the drawings by FIG. 9. As can be seen therefrom, the flow of the layers of molten glass is such that there is a relatively wide line of contact 47 at the union of the marginal edges of upper and lower sheets 38 and 39, thus adding to the strength of the lower corner of the unit. Further, it can be seen from FIG. 2 that, due partly to the removal of the corner portions 46 of upper sheet 38, the corners of the sealed unit are rounded and do not present protuberances which might later require removal in the assembly of the unit in a suitable sash.

In being moved past concentrated heat source to effect the seal described above, upper and lower sheets 38 and 39 are supported in properly spaced relation on a tray 48, which is moved on conveyor 32 forwardly through furnace 34 and past burners 37 in a manner to be described hereinafter. An elevational view of the entire tray 48 is shown in FIG. 13 and an enlarged but fragmentary view of the same can be seen in FIG. 16. However, particular reference is had to FIGS. 10 to 12 for a description of the novel construction of the tray and its respective parts.

In plan, the tray 48 corresponds substantially to the outline of the glass sheets supported thereby. For purposes of illustration, the sheets and tray are shown as being of a square shape. The lower rim 49 of the tray is relatively larger than the upper rim 50 and is rigidly connected thereto by a series of angularly disposed struts 51 at each side of the tray and braces 52 at each corner thereof. Upper rim 50 conforms substantially to lower sheet 39, the marginal edge portions of which are supported on the upper edge of said rim. Additional support may be provided for the suspended central portion of said lower sheet by a rib 53 (FIG. 16) extending between opposite sides of upper rim 50 and having a rounded upper edge in horizontal alignment with the upper edges of said rim.

A pan 54 of sheet metal or other suitable material is secured at each of its edges to struts 51 and braces 52 intermediate upper and lower rims 50 and 49. In this manner, in the case of breakage of the glass sheets, the particles thereof are prevented from falling into the conveyor mechanism or onto the bottom of the furnace. As well, pan 54 serves to shield the bottom of lower sheet 39 from the heat of the furnace to prevent bending or bowing of the suspended central portions thereof. Prior to the placing of lower sheet 39 on the upper rim of the tray, the upper edge of said rim may be coated with colloidal graphite, talc or other suitable material to prevent the marginal edge portions of said sheet from adhering thereto.

Thus, for a purpose to be described hereinafter, the tray 48 is substantially trapezoidal in a transverse cross section. Adjacent the upper rim of the tray and secured between the apices of adjacent struts 51 are a plurality of bearings

55 having vertically bored journal openings 56. Pivotedly mounted within each of the openings are pins 57 having headed portions 58 upon which are carried upper sheet supporting arms 59.

The arms 59 are slidably received in a channel through the upper side of said headed portions 58 and each of said arms is attached thereto by a bolt 60 extending through a slot 61 in said arm and threadedly received in said headed portion. Thus, upon loosening bolt 60, arm 59 may be moved a limited distance in a defined path through the channel of headed portion 58. Of course, upon tightening its respective bolt, each of the arms 59 may be securely locked in place in the desired position.

Each of said arms is indented at its inner end to form a ledge 62 for supporting the marginal edge portions of upper sheet 38 in proper spaced relation to those of lower sheet 39. Handles 63 extend outwardly from the opposite ends of the headed portions of each of the pins 57. Thus, each of the arms may be selectively swung by handles 63 in the plane of sheets 38 and 39 from an upper sheet supporting position, as shown by the three leftmost arms in FIG. 10, to a non-supporting or "knocked-out" position, as shown by the rightmost arm in said figure.

Preparatory to mounting upper sheet 38 above lower sheet 39, each of the arms 59 is swung to the supporting position and, if necessary, is adjusted in a direction perpendicular to the edge of the upper sheet to be supported thereon such that said sheet will be supported by each of the ledges 62 in at least substantially vertically aligned relation with respect to the lower sheet. When both upper and lower sheets 38 and 39 have been properly assembled on tray 48, in the manner described, the tray may be placed upon conveyor 32 so as to be moved through the preheating compartment 33 and furnace 34 and past concentrated heat sources in the form of burner heads on burners 37, as indicated by the broken lines of FIG. 12. To prevent bending or bowing of marginally supported upper sheet 38 during its passage through the furnace, strips of glass cloth (not shown) may be placed over the top thereof to shade all but its marginal edge portions from the concentrated heat sources.

Preheating compartment 33 is supported above conveyor 32 in slightly spaced relation thereto and is provided with suitable interior heating elements (not shown) by means of which sheets 38 and 39 may be preheated, prior to their entry into furnace 34, for a purpose well known in the art. Doors 64 are provided at one side of the compartment for placing the tray and sheets on the conveyor inside the chamber. An exit (not shown) at the side of the compartment facing the entrance 35 of the furnace permits the tray 48 resting on conveyor 32 to be moved forwardly from the compartment to said furnace entrance. Alternatively, of course, sheets 38 and 39 may be properly preheated within the forward end of the furnace, in which case merely changes in temperature control within the furnace would be required.

Conveyor 32 is composed of a series of spaced, horizontally disposed rollers 65 supported at each end on horizontally disposed channels 66 (FIG. 16) secured to the upper ends of uprights 67 which are spaced at intervals parallel to and at each side of furnace 34. Channels 68 are secured to and extend between said uprights for supporting the bottom of said furnace at an elevation intermediate the rollers and floor level. Enlarged feet 69 may be provided for the lower ends of uprights 67 as shown in FIG. 13.

Rollers 65 are preferably hollow cylinders formed of any suitable material and spaced apart along the length of the furnace a distance sufficient to provide adequate support for the length of tray 48 (FIG. 13). The ends of the rollers extend through openings 70 in each side of the furnace and are provided with outwardly projecting spindles 71 which are journaled in bearings 72 mounted on channels 66. Secured to one outer end of each of said spindles is a sprocket wheel 73 adapted to actively en-

gage with the upper run of link chain 74. As best shown in FIG. 16, the upper run of the chain is supported on a longitudinally extending channel member 75 and the lower run thereof on a similar member 76, both of which are secured to uprights 67 outwardly thereof. A guard 77 is secured to members 75 and 76 and may be provided with an upper flange portion 78 for protecting sprocket wheels 73 as well as link chain 74.

Thus, by any suitable power means (not shown) link chain 74 may be moved forward in the direction of the movement of tray 48 through furnace 34 to cause rollers 65 to rotate in a corresponding direction for so moving said tray. It is to be understood, of course, that a similar mechanism may be provided for each straight section of the conveyor 32, in the first and second sealing areas A and B and annealing area C of the furnace. By means of a directional transfer mechanism (not shown) and by coordinating the operation of the driving mechanisms for each conveyor section, a continuous movement may be provided through furnace 34 from the entrance 35 to the exit 36 thereof.

Furnace 34 is of a generally U shape conforming to conveyor 32, as previously mentioned, and is composed of top and bottom walls 79 and 80, respectively, and side walls 81 of any suitable refractory material. Bottom wall 80 is supported by the channels 68 at a level spaced from and below the rollers 65 of conveyor 32, and top wall 79 is elevated above said rollers a distance sufficient to permit the free movement of tray 48 through the furnace as well as the movement of the forward portions of burners 37 through openings 82 in the side walls 81. Shields 83 (FIG. 18) may be provided at the outer side of side walls 81 of the furnace for covering the open spaces in openings 82 around burners 37. Openings 84 in said shields permit the passage of rollers 65 therethrough.

As well, "Selas" type heating elements 85 may be provided in each side wall of the furnace above and below the path of tray 48 (FIGS. 13 and 14) at a number of locations along the length of said furnace for maintaining the respective locations at the desired temperature. Fuel gas for the heating elements 85 may be provided from any suitable source (not shown) to a conduit 86 (FIG. 14) above the furnace and supplied to said heating elements at each side of the furnace by branch pipes 87. The temperature of each area of the furnace may be controlled by any suitable means, such as valves 88 on the branch pipes and proper heat distribution obtained by means of the areas of the furnace above and below rollers 65.

Each of the burners 37 includes a burner head 89 and means for mounting same in proper elevation with respect to upper and lower sheets 38 and 39 on tray 48 when moved therewith, a "knock-out" pin 90 for engaging handles 63 of the upper sheet supporting arms 59 of the tray, in a manner and for a purpose to be described, rails 91 adjacent opening 82 and disposed perpendicular to and outwardly from the side walls 81 of the furnace over which the burner head mounting means may be moved inwardly and outwardly of opening 82 and into operative position with respect to the marginal edges of the glass sheets, and aligning rollers 92 for properly orienting the tray and burner head with respect to one another during movement of the tray therewith.

Rails 91, upon which the burner head mounting means is supported and adapted to be guidably moved, are secured by any suitable means, such as bolts 93, to horizontally extending channels 94 which, in turn, are supported from upright angle irons 95 to form a substantially rectangular table constructed independently of the furnace. The lower ends of the uprights 95 may be provided with feet 96 and cross members 97 (FIG. 16) may be extended between the webs of channels 94 to add rigidity to the table structure. As well, cross members 98 and

99 may be extended between the lower ends of the uprights.

The mounting means for each of burner heads 87 is provided with a base plate 100 having notched portions 101 at each side thereof for slidably engagement with the upper inner edges of rails 91. A series of lower cross bars 102 may be releasably held in engagement with the opposite lower edges of the rails by means of bolts 103 (FIG. 19). Thus, the cross bars 102, in addition to maintaining the burner head and mounting means therefor on rails 91, permits the base plate 100 to be either locked in place or to be moved in frictional engagement over rails 91 into the desired position relative to the furnace.

It is, of course, necessary in practicing this invention that the marginal edge portions of the glass sheets 38 and 39 to be sealed be moved past the burner heads 89 at each side thereof in perfectly aligned relation. That is, both the upper and lower rows of nozzles 104 and 105, respectively, on the burner heads must be in parallel relation to and equally spaced from said marginal edge portions at both sides of the furnace at all times during the passage of the sheets therewith. For this purpose, there is provided, in accordance with this invention, an arrangement whereby the forwardly moving tray 48 will be caused to coat with rollers 92 of the opposed burners 37 to automatically dispose the nozzle rows 104 and 105 in properly aligned relation with respect to the marginal edge portions of the glass sheets.

To be more specific, burner heads 89 on each of the opposed burners are mounted above base plates 100 in such a manner as to be normally resiliently urged inwardly toward one another. In addition, the mounting means for the burner heads are pivotally connected to said base plates so as to be movable outwardly with respect thereto. Thus, when base plates 100 are locked in place on rails 91, burner heads 89 of opposed burners may be caused to move outwardly from one another, and relative to said base plates, from their normal inwardly urged position.

Thus, in practicing this invention, burners 37 may be moved into a position in which the rollers 92 suspended from housings 106 secured to the burner heads 89, will be spaced apart transversely of the furnace a distance just less than the length of the sides of lower rim 49 of tray 48. In this manner, when the tray is moved forwardly in at least approximately aligned relation with the space between opposed rollers, the opposed sides of said rim will coat with the rollers for the opposed burner heads 89, in moving therewith, to cause said burner heads to move outwardly an amount just sufficient to permit the opposite sides of the lower rim of tray 48 to pass through the rollers 92 frictionally engaged thereby. To put it another way, the opposed burner heads will be spread out by tray 48 from their normal position to what may be called an operative or sealing position.

Of course, when tray 48 is so disposed between the rollers 92 and the marginal edge portions of the glass sheets are actually being fused the burner heads 89 are maintained in the operative position by the inwardly urged mounting means therefor. That is, the arrangement of said mounting means above the base plate 100 serves, when said base plate is rigidly locked in place, to constantly maintain the rollers 92 for each of the burner heads in frictional engagement with the opposed sides of rim 49. It will be understood, therefore, that when said tray is disposed between all four rollers, two on each side, the rows of nozzles on the burner heads will automatically be properly aligned with respect to the opposed marginal edge portions of the glass sheets 38 and 39.

Dealing now specifically with the arrangement of the mounting means for each of said burner heads, mounting sleeves 107 and 108 are attached at their inwardly disposed ends to the rear wall of the housing 106 by means of pivotal hinge connections 109. Sleeve 107, disposed

toward the forward (uppermost in FIG. 18) end of the furnace, is relatively shorter than sleeve 108 and is pivotally mounted at its outwardly disposed end above base plate 100 by a hinge connection 110. The longer sleeve 108, on the other hand, is pivotally mounted above said base plate by two similar connections 110, one of which is located at its outwardly disposed end and the other at a point inwardly of the connection for sleeve 107.

One of the hinge connections 109 is shown in detail in FIG. 17 and comprises arms 111 secured to the rear wall of housing 106 and having threaded vertical openings 112. Suitably bored openings in a connecting arm 113 are journaled on opposed hinge pins 114, received in the threaded openings of arms 111. Sleeves 107 and 108 may be fitted over the shank of the connecting arms for each of the hinge connections 109.

Each of the hinge connections 110 is supported above base plate 100 by means of tubular columns 115 integrally cast with said base plate and extending upwardly therefrom, as best shown in FIG. 19. A swinging arm 116 is pivotally mounted from the top of said column by a hinge pin 117, removably received in said column and having a hub portion extending upwardly therethrough, over which a journal opening in one end of said arm is adapted to pivot. The opposite end of swinging arm 116 is suitably bored to receive the hub portion of a similar pin 118 which extends downwardly through a bearing sleeve 119 received in openings through either of the sleeves 107 or 108.

As can be seen from FIG. 18, the tubular columns 115 and axes of hinge pins 117 for each of the connections 110 are disposed in substantial alignment along the longitudinal axis of base plate 100. Thus, in the operative or sealing position of the burner (as shown in said figure), sleeves 107 and 108 are in substantially parallel relation. As well, it will be understood that in swinging on the two hinge connections 110, sleeve 108 will traverse paths which are at all times parallel to one another. On the other hand, it is equally apparent that sleeve 107, swinging on only the single hinge connection 110, will move in paths the directions of which relative to one another will be dependent on the movement of burner heads 89. Thus, there is provided, in a manner to be more fully explained hereinafter, an arrangement for mounting the burner heads which will automatically "give" and subsequently right itself as the burner 37 is contacted by and aligned with a side of tray 48.

As a means for normally urging the mounting means for opposite burner heads inwardly toward one another, tension springs 120 (shown in detail in FIG. 20) are extended between swinging arms 116 on the hinge connection 110 for sleeve 107 and a portion of base plate 100 as well as between swinging arm 116 on the rear connection 110 for sleeve 108 and another portion of said base plate. In both instances, however, the portion of base plate 100, to which one end of spring 120 is attached, is forwardly of the arm to which the other end of the spring is attached. Thus, tension springs 120 provide resilient means for normally urging each of the sleeves inwardly.

Dealing now specifically with one of said tension springs, bracket 121, securely mounted on base plate 100, includes at one end thereof an upstanding arm 122 having an opening through which a pin 123 may be threaded. The tension spring 120 is hooked at one end through an eye on said pin and at the other end to a small plate 124 secured to swinging arm 116. The tension in said spring may be adjusted by the manipulation of pin 123 and lock nuts 125. At the opposite end of bracket 121, upstanding arm 126 receives, through a threaded opening therein, a limit screw 127 which is disposed in alignment with the side edge of arm 116. By means of lock nut 128, the end of said screw may be adjustably positioned, as desired, to limit the position to which swinging arm 116 may be urged inwardly by tension spring 120.

As shown in FIGS. 18 and 20, for example, the burner

head mounting means is in the operative position in which the swinging arms 116 for each of the hinge connections 110 are disposed parallel to one another and perpendicular to the parallel sleeves 107 and 108. In this position, each of the arms 116 is urged outwardly against the tension in springs 129 and is spaced slightly from the end of limit screws 127. On the other hand, in the normal inwardly disposed position of burner heads 89, the adjacent side edges of arms 116 will be in abutting relation with said limit screws such that each of the arms is disposed at least generally obliquely to sleeves 107 and 108. Thus, it will be understood that the front face of burner heads 89, and the rows of nozzles 104 and 105 will be moved from one position parallel to the movement of conveyor 32 and tray 48 supported thereon to another position spaced from but parallel to said first-mentioned position.

Of course, in the normal position, none of the rollers 92 have been contacted by lower rim 49 of tray 48. In the operative position, however, the tray is disposed between all four rollers. Intermediate these positions, only the forward rollers, one on each opposite burner, is engaged by the forward end of the tray. Thus, as the forward end of the tray moves into the engaging position with the forward rollers, the burner head mounting means will be caused to undergo the "give" aforementioned.

Specifically, on each burner head 89 the forward rollers 92 will be moved outwardly causing sleeve 107 to swing on its hinge connection 109. As a result, arm 116 of sleeve 107 will swing in the opposite direction on hinge pin 117 away from its limit screw 127 and assume a position at least approximately perpendicular to the longitudinal axis of base plate 109. As the tray 48 moves further past burner heads 89, its forward end will engage the rear rollers 92 as the forward rollers are maintained in their outwardly disposed position. In compensating for the movement of the rear rollers, each sleeve 108 will be swung on its hinge connection 109 and arms 116 for each of said sleeves will be swung in the opposite direction to assume positions at least approximately parallel to the arm 116 for sleeve 107. Of course, as tray 48 travels still further, lower rim 49 will move out of engaging position with forward rollers 92 and the arm 116 for each sleeve 107 will return to its position in abutting relation with limit screw 127. When the tray is moved its entire length past the rollers, the arms 116 for each sleeve 108 will assume similar positions, at which time the burners will have returned to their normal inwardly disposed position.

As previously mentioned, it is necessary that the rows of nozzles 104 and 105 on opposed burner heads 89 be disposed in perfectly aligned relation to the opposite edge portions of the sheets 38 and 39 during the actual sealing of said edges. That is, it is an important feature of this invention that the flames from the nozzles be directed to the edges of the sheets in a predetermined and constantly maintained relation during the actual sealing thereof.

Therefore, to provide the proper coordination between the aligning of the opposite edges of the glass sheets with the burner heads 89 and the actual sealing of said edges, the tray 48 is specially constructed, in a manner previously described. That is, the cross section of the tray 48 is substantially trapezoidal with lower rim 49 thereof projecting a substantial distance outwardly beyond upper rim 50. As will be more fully understood from FIG. 13, the amount of this projection is slightly greater than the longitudinal distance between rollers 92 on each burner head. In this manner, prior to the passage of any portion of the opposite side edges of the sheets 38 and 39 past the nozzles of the burner heads 89, those portions of lower rim 49 projecting beyond upper rim 50 will have moved said burner heads to the operative or sealing position. In like manner, the burner heads 89 will be maintained in the operative position by the similar projecting portions of lower rim 49 at the rear end of the tray until the entire lengths of the opposite edges have been sealed.

The actual sealing of the marginal edge portions of

upper and lower sheets 38 and 39 is performed progressively along opposed sides of said sheets. That is, as they are passed by the burner heads 89, the marginal edge portions of the sheets are almost instantaneously fused together as the flames from the rows of nozzles 104 and 105 are played therewith. That is, each portion of said opposed edges is moved past the entire length of the upper and lower rows of burner head nozzles and, after having so passed, each of said portions is almost instantaneously fused as its spaced marginal edge portions are rendered molten and caused to unite in a manner previously described.

Upper sheet supporting arms 59 have also been previously described as being movable from a supporting to a non-supporting or "knocked-out" position. For the purpose of progressively engaging the handles 63 of the arms on opposed sides of the tray 48, as it is moved therewith, "knock-out" pins 90 are so supported from each of the opposite burners at the forward sides thereof as to engage said handles just prior to the movement of those portions of the glass sheet marginal edge portions supported thereby past the burner heads 89. That is, with particular reference to FIG. 13, it can be seen that as tray 48 moves past "knock-out" pins 90 prior to moving past the burner head nozzles, each of the upper sheet supporting arm handles 63 will be progressively moved to the "knocked-out" position.

In this manner, the opposed marginal edge portions of the sheets being fused will at all times during the fusing thereof be supported in properly spaced relation. That is, for example, as the supporting arms 59 for the forward end of the upper sheet are removed from their supporting position and said forward end of the upper sheet is in the process of being fused with that of the lower, the remaining lengths of the opposed edges are maintained in properly spaced relation by the remaining arms 59. As well, due to the fact that the fusion takes place almost instantaneously, those portions of the opposite marginal edges, which have passed burner heads 89 and have been transformed into side portions 40, also provide supports for properly spacing the sheet. Thus, by a combination of said fused portions of the sheets as well as supporting arms 59, upper and lower sheets 38 and 39 are at all times during the sealing operation maintained in properly spaced relation.

"Knock-out" pin 90 depends from a rod 129 which extends substantially parallel to sleeve 107 and is slidably received in a bearing sleeve 130 (FIG. 15). Set screws 131 are received through the top of the sleeve for locking rod 129 in place when it has been moved to the desired position longitudinally of the burner head mounting means. Threaded pins 132 depend from sleeve 130 and are received in slots 133 in the upper plate 134 of an "I" shaped support member 135. Lock nuts 136 serve to support the sleeve on said pins 132 in fixed relation above upper plate 134. The lock nuts may be loosened to permit pins 132 to be moved in slots 133 vertically as well as transversely of the burner head mounting means. The lower plate of support member 135 may be secured to rail 91 in any suitable manner.

By means then of the particular apparatus described in connection with FIG. 15, the "knock-out" pin 90 may be moved into any desired position to engage handles 63 of the upper sheet supporting arms 59 at a point along the path of said tray which will permit ledges 62 of said arms to be entirely removed from between glass sheets 38 and 39 prior to the movement of those portions of upper sheet 38 supported by said ledges past the burner heads 89. Thus, as shown in FIG. 13, the pin 90 is spaced slightly forward of burner head 89 such that just after a ledge 62 is entirely removed from a portion of the marginal edges of the glass sheets, flames from the rows of nozzles 104 and 105 will be directed thereto.

Although best results have been obtained by the particular arrangement of the burner head nozzles with re-

lation to the marginal edge portions of the glass sheets disclosed and described herein, it is to be understood that this invention is not restricted thereto. Generally, however, it may be said that the nozzles on the burner heads should be arranged close enough to said marginal edge portions that the flames therefrom will be actually played along said portions of both sheets, such that they will be caused to become molten and bend or curl in substantially the manner previously described.

It has been found that in actual practice, with glass sheets of approximately $\frac{1}{8}$ " thickness and spaced apart approximately $\frac{1}{4}$ ", a permanent seal may be obtained by arranging the burner head nozzles with relation to said sheets in the manner shown in FIG. 12. As shown therein, the nozzles of the upper row 104 are spaced about $\frac{7}{8}$ " above upper sheet 38 and are directed perpendicularly thereto in substantial alignment with the edge of lower sheet 39. The nozzles of the lower row 105 are spaced a similar distance above the edge of lower sheet 39 and are disposed at an angle of about 45 degrees to the plane thereof.

Thus, as the sheets are moved past the burner heads, the flames from the upper row 104 of nozzles will cause the marginal edge portions of the upper sheet to become molten and bend toward those of the lower sheet. Simultaneously, the flames from the lower row 105 of nozzles will cause a relatively smaller part of the marginal edge portions of the lower sheet 39 to curl upwardly. When said marginal edge portions have united and reached approximately the position shown in FIG. 6, the flames from the upper row of nozzles will further cause the united portions to become more molten and the line of fusion 47 to increase, as previously described with respect to FIG. 7. At the very final stages of the fusing, the flames from the lower row of nozzles will be played along said line of fusion to perfect the seal between the side of the sheets.

The sealed molten marginal edge portions of the sheets may be "set" and the suspended inner portions prevented from sagging by a jet of air directed along the lengths thereof to rapidly cool the same shortly after they have passed the burner head 89. Air for this purpose may be supplied from any suitable source (not shown) and carried through a pipe 137 (FIG. 18) extending along the rear side of the burner head mounting means to a nozzle 138 having a vertically directed opening disposed above the path of the marginal edge portions of the glass sheets. The pipe 137 may be supported along its length from a bracket 139 upstanding from rail 91 and a mounting sleeve 140 secured to and spaced from the rear side of burner head 89.

Additional aligning rollers 141 are suspended from supports 142 secured to the side walls 81 of the furnace at each side thereof forwardly of each of the sealing areas A and B and in substantial alignment with the space between the normally urged rollers 92 on burners 37. The rollers 142 may be spaced apart a distance slightly greater than the width of the lower rim of tray 48 for properly aligning the same prior to its movement into engaging relation with rollers 92. If desired, the rollers 141 may be suspended from supports 142 in inwardly converging relation.

It will also be understood that in sealing glass sheets 38 and 39 entirely around the marginal edges thereof, first one pair of opposite edges and then the other must be fused at sealing areas A and B, respectively. It is contemplated that the burners 37 at each of the stations may be identical. It is further contemplated that at the corner of the furnace 34 between sealing areas A and B as well as at the corner between sealing area B and annealing area C, there may be provided, in cooperation with conveyor 32, a suitable directional transfer device whereby the direction of movement of tray 48 may be altered 90 degrees.

Of course, a device of this kind may take any number of forms in which, for example, the forward end of the tray 48 is caused to actuate automatic means for transferring said tray from one section of conveyor 32 to another. At any rate, the particular mechanism for so indexing tray 48 does not form a part of this invention and is not illustrated herein. For that matter, rather than being constructed in the substantial "U" shape shown, if space permits, furnace 34 and conveyor 32 may be constructed in either an "L" shape or a straight line.

Regardless of the particular shape of the furnace and conveyor, however, tray 48 is moved continuously through the furnace in a manner to expose first one and then the other pair of opposite edge portions of glass sheets 38 and 39 to the flames from the opposed burners 37. Although the tray 48 has been shown herein as substantially square, it will be understood that the position of the burners may be adjusted to accommodate trays of most any rectangular shape.

Intense localized heating for sealing the marginal edge portions of the glass sheets is supplied by flames from an oxygen and natural gas mixture. For this purpose, the oxygen and gas for each of the burner heads 89 are supplied from a suitable source (not shown) through pipes 143 and 144, respectively, to a mixing chamber 145. From the mixing chamber 145, a conduit 146 extends toward burner head 89 and carries the oxygen-fuel mixture to a flexible hose 147 which in turn is connected to one end of an oxygen-fuel inlet pipe 148. The inlet pipe 148 extends through the entire length of a concentrically arranged conduit 150 and is threadedly received at its other end in the rear wall of the burner head, as shown in FIG. 22. Both the inlet pipe and surrounding conduit 150 are extended through an opening 149 in the rear wall of housing 106. Also, inlet pipe 148 may be supported toward its rear end on a block 151 which in turn may be supported by struts 152 extending longitudinally from the rear wall of housing 106.

A coolant may be supplied from a suitable source (not shown) through a pipe 153 extending longitudinally of conduit 150 and threadedly received in the rear wall of the burner head 89 at a point to one side of the threadedly received end of oxygen-fuel inlet pipe 148. The coolant may be discharged from the burner head, after circulating through the cast manifold thereof, in a manner to be described hereinafter, through a passage 154 in conduit 150, which passage is concentrically arranged around the length of oxygen-fuel inlet pipe 148 extending through said conduit. An elbow 155 (FIG. 22) connects the passage 154 with a coolant outlet pipe 156 from which the coolant may be carried to a suitable point of disposal.

Additional means are provided whereby the burner head 89 may be moved, independently of the burner head mounting means, inwardly and outwardly of the marginal edge portions of the glass sheets. For the purpose of so adjusting the burner head independently of its mounting means, an adjusting rod 157 extends longitudinally above conduit 150 and is secured at its forward end in a mounting bracket 158 on the top wall of housing 106. As shown in FIG. 21, a reduced portion at the forward end of the rod 157 is received between upper and lower clamping members 159 and 160, releasably held in interfitting relation by pins 161. The adjusting rod 157 is provided with a threaded portion at its rear end which is received in a bracket 162 mounted above conduit 150.

Flange 163 (FIG. 22) on the side walls of housing 106 at the front face thereof are provided with bearing sleeves 164 in their outer legs. Rods 165 extend rearwardly from wing portions 166 at each side of the burner head 89 and are slidably received in the bearing sleeves 164 of the housing 106. Thus, a rotative movement of adjusting rod 157 will result in the movement of the burner head inwardly or outwardly of its mounting means, as desired.

Turning now to the construction of each of the burner

heads 89, and with reference to FIGS. 21 to 27, lower walls 167 and 168 thereof are disposed angularly to one another to direct flames from the upper and lower rows of nozzles 104 and 105, respectively, in proper impinging relation to the marginal edge portions of glass sheets 38 and 39. A series of passages are provided interiorly of the burner head for the proper distribution of the oxygen-fuel mixture from inlet pipe 148 to the individual nozzles 169. Another series of passages are provided for distributing the coolant from pipe 153 through the burner head, in substantially surrounding relation to the oxygen-fuel passages, to passage 154.

Passage 170 extends horizontally and transversely of the burner head 89 as a continuation of the threaded socket for oxygen-fuel inlet pipe 148 to a point just short of the front wall of said burner head. A passage 171 is bored vertically from the upper wall of the burner head to intersect said threaded socket and extend downwardly therefrom to a horizontally and longitudinally extending distributor passage 172 for the lower row of nozzles 105. Threaded outlet passages 173 project downwardly from distributor passage 172 and perpendicular to the lower wall 168 of the burner head at equally spaced locations along the length thereof to provide sockets for threaded shanks on each of the nozzles 169 of the lower row 105.

Passage 174 is bored upwardly from and perpendicular to the lower wall 167 of the burner head 89 to intersect with the end of horizontally extending passage 170. Distributor passage 175 for the upper row of nozzles 104 extends horizontally of the burner head and parallel to distributor passage 172 to cross the passage 174 at a point below passage 170. Outlet passages 176 (FIG. 22) project downwardly from the distributor passage 175 in parallel relation to passage 174 at equally spaced locations along said distributor passage and are threaded at their lower ends similarly to the lower end of the passage 174, to receive the shanks of the nozzles 169 of the upper rows 104.

As best shown in FIG. 21, the nozzles 169 of the upper row 104 are spaced apart from one another a distance equal to that of the spacing between the nozzles of the lower row 105. As well, the nozzles of the upper row are staggered with relation to those of the lower in such a manner that the impinging flames from said upper and lower rows of nozzles will provide a substantially continuous, longitudinally extending flame to the marginal edge portions of the glass sheets 38 and 39 moving therewith.

Dealing now with the circulation of the coolant through burner head 89, it can be seen that a short passage 177 extends inwardly as a continuation of the threaded socket for coolant inlet pipe 153 in the rear wall of said burner head. Another short passage 178 (FIG. 24) is bored vertically from the upper wall of the burner head to intersect at its lower end with the end of horizontal passage 177, and is intersected at its upper end by a horizontally extending distributor passage 179 which is bored from the rear wall of the burner head to a point just short of the front wall thereof.

A series of passages, consisting of a relatively large passage 180 and smaller passages 181 and 182 extend horizontally and longitudinally from distributor passage 179 in a direction away from the oxygen-fuel passage 170. Each of said passages may be bored parallel to one another and in properly spaced relation from a side wall (rightmost in FIG. 22) of the burner head. At points just short of said side wall, another series of passages 183, 184 and 185 (FIG. 22) may be bored vertically through the upper wall of the burner head to intersect horizontal passages 180, 181 and 182, respectively.

Passage 183, corresponding in diameter to passage 180, extends downwardly therefrom to a point just short of lower wall 168 of the burner head where it connects with a relatively smaller passage 186 extending horizon-

tally and longitudinally the entire length of the burner head. At its connection with the smaller passage 186, vertical passage 183 also leads to a similar passage 187 through a short passage 188 (FIG. 24) which may be bored from the rear wall of the burner head parallel to lower face 168 thereof. Thus, passages 186 and 187, disposed on opposite sides of the lower row of nozzles, may be bored through the entire lengths of the burner head.

The opposite (leftmost in FIG. 22) ends of passages 186 and 187 are connected by a short passage 189 (FIG. 25) corresponding to passage 188 at the opposite end of the burner head, which leads to a vertically bored passage 190, corresponding to passage 183. Toward the upper end of passage 190 adjacent the upper wall of the burner head, a passage 191 extends inwardly and horizontally therefrom, in substantial alignment with passage 180, and intersects at its opposite end with a collecting passage 192 (FIG. 26), which extends transversely of the burner head substantially parallel to passage 170 at the side thereof opposite from the passage 177.

Vertically bored passages 184 and 185 extend to points just short of the lower wall 167 of the burner head 89 and intersect, respectively, with one end of horizontally and longitudinally extending passages 193 and 194 disposed at opposite sides of the upper row of nozzles 104. Similarly to passages 186 and 187, at opposite sides of the lower row of nozzles, passages 193 and 194 may be bored through the entire length of the burner head. Just short of the opposite side wall (leftmost in FIG. 22) of the burner head, the opposite ends of passages 193 and 194 intersect, respectively, with vertically bored passages 195 and 196, corresponding to vertical passages 184 and 185. The passages 195 and 196 are intersected by one end of horizontally and inwardly extending passages 197 and 198 (FIG. 25), respectively, which are in substantial alignment with passages 181 and 182 extending from distributor passage 179. The opposite ends of passages 197 and 198 connect with collecting passage 192 at points outwardly (rightmost in FIG. 26) of passage 191.

The collecting passage 192 may be bored from the rear wall of the burner head to a point adjacent the front wall thereof to accommodate intersecting passages 191, 197 and 198. A passage 199 may be bored vertically from the top wall of the burner head to intersect with and extend below collecting passage 192, as shown in FIG. 26, a distance sufficient to permit horizontally disposed coolant outlet passages 200 to connect the lower end thereof to a portion of passage 154 in conduit 150 adjacent recess in the rear wall of the burner head into which said conduit is fitted.

Thus, each burner head 89 comprises a cast manifold having a first series of passages from which an oxygen-fuel mixture may be distributed to two rows of nozzles on the lower walls thereof and a second of passages through which a coolant may be continuously circulated in substantially surrounding relation to said first series of passages. For example, coolant passages 193 and 194 are disposed along opposite sides of the entire length of oxygen-fuel distributor passage 175 as well as the passages 171 to the upper row 104 of nozzles. Similarly, coolant passages 186 and 187 are disposed along opposite sides of the oxygen-fuel distributor passage 172 and the passages 169 to the lower row 105 of nozzles.

As previously described, each of the passages may be bored from the walls of the burner head permitting said head to be integrally cast. The outer openings of said passages may be plugged in any suitable manner, and all but the rear walls of the burner head may be covered with a thin metallic coating 201.

As mentioned previously, a dehydration hole 42 is disposed toward one corner of one of the glass sheets. This hole serves, during the passage of the marginally sealed glazing unit 31 from the second sealing area B and through the annealing area C, as a "breather" per-

mitting the air in enclosed space 41 to adjust itself to varying temperatures in the furnace 34. Upon removal of the marginally sealed unit from the furnace, the space 41 may be dehydrated and the hole 42 hermetically sealed to seal off said space in its dehydrated condition. A number of different well known processes may be used in this final step of dehydrating and hermetically sealing the space between the glass sheets 38 and 39, and the size and shape of the hole 42 will generally depend on the particular process selected. However, since none of these processes forms a part of this invention, any suitable means may be employed.

Reviewing now the entire process of this invention by which spaced sheets of glass may be sealed around their marginal edges to produce an hermetically sealed glazing unit 31, initially the marginal edge portions of a sheet of glass 39 are placed on the upper edges of the upper rim 50 of tray 48. Arms 59 of the tray are then swung into supporting position such that the marginal edge portions of another sheet 38 may be supported on the ledges 62 of said arms in properly spaced and vertically aligned relation above the sheet 39.

The upper surface of the upper sheet 38 may be shaded with glass cloth or the like and the tray 48, with both sheets supported thereon, placed in the preheating compartment 33 in such a manner as to be in substantial alignment with opening 35 in the furnace 34 and the space between rollers 141 as well as the space between the first set of opposed burners 37 at sealing area A. The temperature of the compartment 33 is maintained at about 575 degrees Fahrenheit to properly preheat the glass sheets 38 and 39 prior to their entry into the furnace. Of course, as mentioned previously, the preheating of the glass sheets may be performed in the forward end of the furnace, eliminating the need for a separate compartment.

In any case, however, as the tray 48 is moved forwardly on conveyor 32 and past aligning rollers 141, the glass sheets 38 and 39 are progressively raised to a temperature slightly short of the annealing temperature which, in most cases, is about 1000 degrees Fahrenheit. That is, the sheets are heated to a level just short of their "strain" point in moving into the first sealing area A.

As the tray moves into engaging relation with the opposed burners 37 of the first sealing area A, which have been properly adjusted in the manner described, the opposite sides of the lower rim 49 of the tray will engage rear rollers 92 on the opposed burners to spread said burners from the normal to the operative position. As tray 48 moves forwardly out of engaging relation with the first set of burners, said burners will return or right themselves to the normal position.

During the movement of the tray past the first set of burners when they are disposed in the operative position, the marginal edge portions of the pair of opposite sides of the glass sheets adjacent said burners will be progressively fused, as the arms 59 supporting said opposite marginal edge portions of the upper sheet 38 are "knocked-out" and flames from burner head nozzles 169 are played therealong in the manner described.

As the tray 48 moves from the first sealing area A to the directional transferring mechanism at the corner between said first sealing area and the second sealing area B, upper sheet 38 will be properly supported above lower sheet 39 on one pair of opposite sides by the marginal edge portions of both sheets which have been almost instantaneously fused at the first sealing area to form side portions 40 and on the other pair of opposite sides by arms 59. At the above-mentioned corner of the furnace, the tray 48 will be automatically transferred by suitable mechanism from the first section of conveyor 32 to a second section which travels through the second sealing area B in a direction disposed at 90 degrees to that of the first section. Thus, as tray 48 enters the second sealing area B, it too will be traveling in a path

at 90 degrees to its path through the first sealing area A. In this manner, the unfused pair of opposite marginal edge portions will be aligned with the direction of movement of the tray and the fused portions will be perpendicular thereto. Thus, with opposed burners 37 of the second sealing area B in properly adjusted position and the temperature of said area raised to approximately the same level as sealing area A, the tray 48 will be moved on conveyor 32 past said second set of burners and the unfused pair of opposite marginal edge portions of the glass sheets will be fused in the same manner as were the first pair of marginal edge portions at the first sealing area A.

Thus, it will be understood that as tray 48 moves out of engaging relation with the second set of burners 37 of sealing area B, glass sheets 38 and 39 will be sealed entirely around their marginal edge portions to form enclosed space 41. As the marginally sealed sheets move into the second corner of furnace 34 between sealing area B and annealing area C, a directional transferring device, similar to the one disposed in the first corner of the furnace, will cause the movement of tray 48 to be changed another 90 degrees.

In its oriented position, tray 48 will be moved on the third section of conveyor 32 through the annealing area C. In the annealing area, the temperature of the furnace is accurately controlled in such a manner that it will be caused to drop gradually from about 960 degrees Fahrenheit at the end of said area adjacent sealing area B to about 295 degrees adjacent the exit 36 of the furnace for treating the glass sheets for a purpose well known in the art.

Of course, as the marginally sealed unit 31 is removed from the conveyor 32 at the end of the furnace, it may be moved to any suitable location for dehydrating the space 41 therebetween and hermetically sealing hole 42, as previously mentioned.

It is to be understood that the forms of the invention disclosed herein are to be taken as the preferred embodiments thereof, and that various changes in the shape, size and arrangement of parts may be resorted to without departing from the spirit of the invention.

We claim:

1. A method of producing multiple sheet glazing units, which comprises supporting the marginal edge portions of one sheet of glass in spaced relation above those of another glass sheet, moving said marginal edge portions of the sheets as a unit past a heat source which heats said marginal edge portions and causes them to be fused to one another, and progressively removing a portion of the support for the upper sheet nearest the heat source prior to movement of the previously supported marginal edge portions of said sheets past said heat source while retaining support for the sheet along areas farther removed from said heat source until the marginal edge portions are sealed substantially along their entire length.

2. A method of producing multiple sheet glazing units, which comprises supporting a marginal edge portion of an upper sheet of glass in spaced and outwardly projecting relation above that of a lower sheet, directing a flame from a concentrated heat source downwardly onto the marginal edge portion of the upper sheet in a direction substantially perpendicular to the plane of said sheet and in substantial alignment with the edge of said lower sheet, and simultaneously directing an additional flame downwardly onto the marginal edge portions of said lower sheet at an angle to the plane of said lower sheet.

3. A method of producing multiple sheet glazing units which comprises, supporting the marginal edge portions of one sheet of glass in spaced relation above the corresponding portions of another glass sheet, moving the marginal edge portions of both of said sheets at opposite sides thereof past a group of concentrated heat sources to cause said edge portions to be sealed together, removing

the supports for said marginal edge portions of the upper sheet just prior to their movement past said group of heat sources, orienting said sheets to sequentially dispose the other marginal edge portions of both sheets at the other opposite sides thereof in alignment with other groups of concentrated heat sources, sequentially moving said other marginal edge portions of both sheets past said other groups of concentrated heat sources to cause said other edge portions to be sealed together, and sequentially removing the supports for said other marginal edge portions of the upper sheet just prior to their movement past said other groups of concentrated heat sources.
